DISPLAY HOLDER FOR COINS

John O. Evans III, Michigan City, Ind.

Application April 16, 1956, Serial No. 578,340

6 Claims. (Cl. 206—83)

This invention relates to a display holder for coins, more particularly to a holder for use by coin collectors for storing, preserving and exhibiting collections of coins.

An object of the invention is to provide a holder for coins, tokens, medallions and the like that will accommodate a relatively large number of coins in a small space.

Another object is to provide a coin holder in which coins may be stored conveniently and in which the stored coins may be exhibited and studied without removing the coins from the holder. Coins stored in the holder may be viewed from both the observe and reverse sides. Also, the edges of the coins stored in the holder may be viewed while the coins are left in place.

Another object of the invention is to provide a transparent coin holder in the form of a page or leaf of a book, the coin holder being constructed and adapted to fit into the conventional loose leaf-type binder or post-type binder.

Another object of the invention is to provide a display coin holder that will receive and hold a variety of coins of different size, within wide limits.

Still another object of the invention is to provide a coin holder of the character described that is simple and inexpensive to manufacture and that can be supplied to numismatists at a reasonable and attractive price.

Heretofore, a variety of coin holders have been manufactured and made available to the public. One such type of known coin holder is a stiff cardboard page which has circular recesses cut to the diameter of the coins to be received. Coins are pressed into the recesses for retention therein and are visible only from the front of the page, the back of the page being covered and, hence, obscuring the backs of the coins. In this known type of coin holder, the faces of the coins that are visible are unprotected by any window-like material and, thus, are subject to damage by finger marks, dust, scratches and the like. Additionally, the bottom of the coin recesses are usually coated with glue to retain the coin in the recess; and this glue causes the coins to tarnish and become corroded.

Another known type of coin holder is in the form of a thick cardboard page having coin-receiving holes extending entirely through the cardboard. The front and back openings of the holder are covered by transparent slides which can be removed for insertion of coins and then replaced. While such coin holders permit both the observe and reverse faces of the coin to be viewed, they do not permit the edge to be seen. Also, their construction is complicated and, hence, they are relatively expensive.

The aims, objects and advantages of the present invention, as set forth hereinbefore and as may appear hereinafter, are realized, and the defects and shortcomings of the known coin holders are met, in the coin holder of the present invention, which is a display holder for coins including a first sheet of transparent, flexible, plastic material and a second sheet of transparent, flexible, plastic material coextensive with and positioned in juxtaposed

2

relation to the first sheet. The plastic sheets in this relation have means for securing the sheets together along a first set of spaced parallel lines and along a second set of spaced parallel lines intersecting said first set of lines to define coin-containing pockets. At least one of the sheets of plastic material is cut through to provide slits intermediate the lines along which the sheets are secured together to provide openings for the pockets for insertion and removal of coins.

10 Preferably, the coin holder is rectangular or square in shape and the pockets are also of rectangular configuration. The slits that provide the pocket openings preferably extend entirely across the pockets and are positioned more or less parallel to and midway between opposed edges of the pockets. Usually, the back sheet of plastic material has the pocket openings, and the front sheet is left uncut. In the exemplary embodiment of the invention, to be described hereinafter, the coin holder has a reinforced section along one edge that is provided with spaced holes so that the holder may be secured in a conventional ring binder, or the like.

15 The invention will be described in greater particularity with reference to the accompanying drawing, showing by way of illustration one form of display coin holder in accordance with the invention.

20 In the drawing:

Fig. 1 is a front elevational view of the exemplary coin holder;

25 Fig. 2 is a sectional view taken along the line 2—2 of Fig. 1 looking in the direction of the arrows; and

Fig. 3 is a sectional view taken along the line 3—3 of Fig. 1 looking in the direction of the arrows.

30 Referring to the drawing, particularly to Fig. 1, the coin holder shown is of rectangular configuration. It has a front sheet 10 of transparent, flexible, plastic material such as cellophane, plasticized vinyl synthetic resin sheeting, cellulose acetate or cellulose nitrate plasticized sheet material or other equivalent transparent, flexible, plastic sheet. The coin holder also has a back sheet 11 of similar transparent, flexible sheet material. The front and back sheets 10 and 11 are of the same size and shape and are laid together in juxtaposition with their edges adjoining.

35 The juxtaposed sheets are then secured together, preferably by sewing with thread along the marginal portions 12, 13, 14 and 15. A line of stitching 16 extends from the bottom line 12 to the top line 14 and is spaced inwardly from the line of stitching 15 at the left-hand edge 40 of the holder leaving an open space 17 at the lower left-hand corner of the holder. An elongated rectangular reinforcing plate 19, which can be formed from cardboard, metal, plastic material or the like, is inserted in the pocket 18. Vertically spaced holes 20 and 21 are 45 punched through the sheets 10 and 11 and the reinforcing plate 19. These holes are the means by which the holder is accommodated in a conventional ring or post binder, not shown.

50 The particular holder shown, is divided into sixteen rectangular pockets 22 by means of equally spaced vertical stitch lines 23, 24 and 25 which are parallel to each other and parallel to the left and right sides of the holder. These, together with the equally spaced, horizontally extending stitch lines 26, 27 and 28 delineate the coin receiving pockets 22.

55 While the embodiment of the invention shown in the drawing has the front and back sheets secured together by stitch lines, it will be understood that these sheets may be secured together in any other suitable way, as by providing lines of adhesive corresponding to the stitch lines shown or, if the sheet material is thermoplastic, by weld-

ing the front and back sheets together along lines corresponding to the stitch lines.

Prior to assembly of the front and back sheets, the back sheet is provided with four horizontal slits: 29, 30, 31 and 32, which are exaggerated in the drawing for purposes of clarity. These slits are cut by a scissors or knife and extend from the right-hand edge of the sheet to points intersecting the proposed location of the stitched line 16. These slits are so positioned that they will substantially bisect each of the pockets 22 that are formed by the stitching pattern. It will be seen from Figs. 1 and 3 that, in the assembled construction, the slits and stitching provide flaps 33 and 34 substantially equal in area.

In Figs. 1 and 3, a coin 35 is shown in position in one of the pockets 22. The coin is inserted in the pocket by opening the lower flap 34, for example, and sliding the coin into the bottom of the pocket. Thereafter, the upper flap 33 is pulled over the top of the coin and allowed to resume its normal substantially flat position, as shown in the drawing. The plastic material of which the sheets 10 and 11 is made is of sufficient strength to permit this operation to be performed without tearing the sheet or effecting substantial permanent deformation thereof.

The width of the pocket 22 in the direction parallel to the slit 29 is made sufficiently greater than the height of the pocket so as to allow the pocket to contract inwardly in a horizontal direction when a flap is laid over a coin being placed in or removed from the pocket. The pocket will thus easily accommodate a coin having a diameter substantially equal to the height of the pocket and, of course, it will accommodate a coin of lesser diameter easily. Thus, the pocket 22 will hold and retain coins varying in diameter from slightly over one-half the height of the pocket to slightly less than the full height of the pocket; in this range of coin diameters both flaps 33 and 34 cover some portion of the coin in the pocket so that the coin cannot fall out of the pocket through the slit 29. When the slit 29 is positioned substantially half way between the stitch lines 14 and 26, forming the upper and lower margins of the pocket 22, a large range of coin sizes can be inserted in the pockets without danger of losing them, no matter which way the page or coin holder is turned.

I have found that if the width of the pocket 22 is about one and one-quarter times as great as its height, the pocket will permit ready insertion and removal of a coin having a diameter only very slightly less than the height of the pocket. Practical limits for this so-called aspect ratio of width to height are from one and one-eighth to one and one-half.

It will be seen that the coin 35 may be viewed from the front or back of the holder with equal facility and that the edges of the coin may also be viewed through the transparent sheets 10 and 11.

From the foregoing description it will be seen that the invention provides a display coin holder that fully accomplishes the objects of the invention and makes available a device eminently suited for storing and displaying one or more coins. It will also be seen that modifications can be made in the light of the description of the illustrative embodiment without departing from the spirit and scope of the invention.

For example, a coin holder designed to hold but a single coin and having only one pocket can be readily constructed in accordance with the principles of the invention. Also, the coin holding pockets may be oriented at right angles to the orientation shown in the drawing, that is, the slits and long dimension of the pockets may run vertically instead of horizontally. Moreover, the slits may be cut in the front plastic sheet 10 instead of in the back sheet 11, if desired. Or, alternate slits may be alternately cut in the front and back sheets. Preferably, the slits extend continuously through the line of pockets in order that the longer dimension of each pocket

may be kept to a minimum for considerations of economy of space and material.

It will also be apparent that the front and back sheets 10 and 11 of the coin holder need not be separate elements prior to assembly of the holder. Instead, a single sheet of transparent, flexible, plastic material twice as large as the intended size of the holder can be folded on its center line to provide front and back elements for the coin holder that are joined along the fold line which forms one edge of the completed holder. Therefore, in the claims, the recitation of "first" and "second" sheets is intended to include structures wherein the "first" and "second" sheets are joined along one edge of the holder as well as structures wherein the "first" and "second" sheets are separate elements.

I claim:

1. A display holder for coins comprising a first, transparent, flexible sheet of plastic or similar material, a second, transparent, flexible sheet of plastic or similar material coextensive with and positioned in juxtaposed relation to said first sheet, means securing said sheets together along a first set of spaced parallel lines and along a second set of spaced parallel lines intersecting said first set of lines to define coin-containing pockets, and slit means through at least one of said sheets intermediate said securing means, said slit means extending across each pocket and intersecting and crossing said sheet securing means at opposite edges of each pocket to provide openings for said pockets for insertion and removal of coins.

2. A display holder for coins comprising a first, rectangular, transparent, flexible sheet of plastic or similar material, a second, rectangular, transparent, flexible sheet of plastic or similar material coextensive with and positioned in juxtaposed relation to said first sheet, stitch means securing said sheets together along a first set of spaced lines running parallel to one edge of said sheets and along a second set of spaced parallel lines intersecting said first set of lines at right angles thereto to define a plurality of rectangular coin-containing pockets, and slit means through one of said sheets parallel to one of said sets of stitch lines and positioned substantially centrally between adjacent stitch lines providing openings for said pockets for insertion and removal of coins, said slit means extending continuously through a plurality of said pockets and intersecting and crossing said stitch lines at opposite edges of the pockets.

3. A display holder for coins comprising a first, rectangular, transparent, flexible sheet of plastic or similar material, a second, rectangular, transparent, flexible sheet of plastic or similar material coextensive with and positioned in juxtaposed relation to said first sheet, stitch means securing said sheets together along a first set of spaced lines running parallel to one edge of said sheets and along a second set of spaced parallel lines intersecting said first set of lines at right angles thereto to define a plurality of rectangular coin-containing pockets, slit means through one of said sheets parallel to one of said sets of stitch lines and positioned substantially centrally between adjacent stitch lines providing openings for said pockets for insertion and removal of coins, said slit means extending continuously through a plurality of said pockets and intersecting and crossing said stitch lines at opposite edges of the pockets.

5. A display holder for coins comprising a first, rectangular, transparent, flexible sheet of plastic or similar material, a second, rectangular, transparent, flexible sheet of plastic or similar material coextensive with and positioned in juxtaposed relation to said first sheet, stitch means securing said sheets together along a first set of spaced lines running parallel to one edge of said sheets and along a second set of spaced parallel lines intersecting said first set of lines at right angles thereto to define a plurality of rectangular coin-containing pockets, slit means through one of said sheets parallel to one of said sets of stitch lines and positioned substantially centrally between adjacent stitch lines providing openings for said pockets for insertion and removal of coins, said slit means extending continuously through a plurality of said pockets and intersecting and crossing said stitch lines at opposite edges of the pockets, means including portions of said sheets defining an elongated reinforcing plate pocket between said sheets and extending substantially along and adjacent to an edge of said sheets of plastic material, a reinforcing plate received in said elongated pocket, and means providing spaced holes aligned through said sheets and said reinforcing plate for retention of said display holder in a ring binder.

4. A display holder for coins comprising a first, rectangular, transparent, flexible sheet of plastic or similar material, a second, rectangular, transparent, flexible sheet

of plastic or similar material coextensive with and positioned in juxtaposed relation to said first sheet, stitch means securing said sheets together along a first set of spaced lines running parallel to one edge of said sheets and along a second set of spaced parallel lines intersecting said first set of lines at right angles thereto to define a plurality of rectangular coin-containing pockets each having a greater width than height, each said pocket having slit means extending across the width thereof and through one face thereof, said slit means being positioned substantially centrally of the pocket and parallel to the stitch lines defining the top and bottom edges of said pocket and extending continuously through a plurality of said pockets and intersecting and crossing said stitch lines at opposite edges of the pockets.

5. A display holder for a coin comprising a first, transparent, flexible sheet of plastic or similar material, a second, transparent, flexible sheet of plastic or similar material positioned in juxtaposed relation to said first sheet, rectangular means securing said sheets together to define a rectangular coin-receiving pocket between said sheets, said pocket having a greater width than height, and slit means extending across the width of said pocket through one face thereof and being positioned substantially centrally of the pocket and parallel to the top and bottom edges thereof, said slit means intersecting and crossing

said sheet securing means at opposite edges of the pocket.

6. A display holder for coins comprising a first, rectangular, transparent, flexible sheet of plastic or similar material, a second, rectangular, transparent, flexible sheet of plastic or similar material coextensive with and positioned in juxtaposed relation to said first sheet, stitch means securing said sheets together along a first set of spaced lines running parallel to one edge of said sheets and along a second set of spaced parallel lines intersecting said first set of lines at right angles thereto to define a plurality of rectangular coin-containing pockets, and slit means through one of said sheets parallel to one of said sets of stitch lines and positioned substantially centrally between adjacent stitch lines providing openings for 10 said pockets for insertion and removal of coins, said slit means extending continuously through a plurality of said pockets and intersecting and crossing said stitch lines at opposite edges of the pockets, each of said pockets having a dimension measured parallel to said slit means of from 15 one-and-one-eighth to one-and-one-half times the dimension of the pocket measured at right angles thereto.
